INKWELL

Virgil Eckhart, Ottawa Shores, Mich., assignor to Preferred Products Company, Toledo, Ohio, a corporation of Ohio

Filed Apr. 27, 1959, Ser. No. 55,680

Term of patent 14 years

(Cl. D74—6)

FIG. 1.

FIG. 2.

FIG. 3.

Fig. 2 is a top plan view thereof; and

Fig. 3 is a side elevational view.

I claim:

The ornamental design for an inkwell, substantially as shown.
